WOODEN PANEL

George M. Hunt, George C. McNaughton, and
Theodore J. Martin, Madison, Wis.; dedicated
to the free use of the People in the territory of
the United States

Application August 6, 1942, Serial No. 453,776

2 Claims. (Cl. 20—91)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to us of any royalty thereon.

We hereby dedicate the invention herein described to the free use of the people in the territory of the United States to take effect on the granting of a patent to us.

This invention relates to wooden panels and to the manner of constructing such a panel from edge joined strips.

Ordinarily, wooden panels are formed from a plurality of strips cut lengthwise of the grain and joined edge to edge. Glues, such as animal, starch, casein, vegetable protein, and many synthetic resins, when used for joining, release their bond when exposed to fire. This, together with shrinkage of the wood, which is greater in the transverse than in the longitudinal direction of the grain, causes the joints to open, forming cracks through which the fire passes, thus greatly reducing the fire resistance of the panel.

Prior attempts to improve the fire resistance of panels have been made. For example, the strips have been joined with a tongue and groove joint. However, this is wasteful of material and does not satisfactorily increase the fire resistance. When the strips shrink away from each other and the tongue burns through, cracks yet remain. In other attempts sheets of woven asbestos cloth have been placed on a panel or directly under the crossbands. However, this is expensive and involves difficulties in gluing or otherwise attaching the asbestos sheets.

An object of this invention is to improve the fire resistance of wooden panels by making the joints between component pieces less vulnerable to fire.

Panels constructed according to this invention are suitable for use as solid-core flush doors, bulkheads, etc., and are specifically illustrated in the accompanying drawing in which

Figure 1 is a perspective sectional view of a corner portion of the panel.

Figure 2 is an exploded view of a pair of strips 50 showing the edged joint structure, and

Figure 3 is an exploded view of a pair of strips showing the end to end joint structure.

In the drawing, 1 represents wooden strips of any desirable dimensions and number. The strips are formed at the joining edges with matching grooves 2 in which are fitted fire-resistive strips or splines 3, made of fire-resistive material, such as asbestos millboard (which is preferred), asbestos cloth, glass cloth, mica, porcelain, fire-resistive wood or plywood, or materials coated with fire-retarding preparations, etc. Such materials are both non-combustible and non-conductive. Thus the splines bridge the seams or joints between adjacent strips to block passage of fire.

The strips are also formed at their joining ends with matched cross grooves 4 in which are fitted short pieces 5 of fire-resistive material bridging the end joints. It is not essential, however, that the end joints be fire-proofed and the end grooves 4 and pieces 5 may be omitted. The strips are glued together, and are provided with suitable crossbands 6 to hold them assembled, since the splines, because of the nature of the material, are not structurally strong. The crossbands are covered with suitable veneers 7.

The particular arrangements of parts herein disclosed are illustrative of but one embodiment of the invention, which is not limited thereto except as required by the appended claims.

Having thus described our invention, we claim:

1. A panel comprising wooden strips joined along their edges with glue, each strip having at least one groove in its edge matching groove in the edge of the adjoining strip, an asbestos millboard spline fitted in the matching grooves and bridging the joint between the strips, crossbands covering the strips on both sides of the panel, and veneers covering the crossbands.

2. A panel comprising wooden strips joined along their edges, each strip having at least one groove in its edge matching the groove in the edge of the adjoining strip, an asbestos millboard spline fitted in the matching grooves and bridging the joint between the strips, crossbands covering the strips on both sides of the panel, and veneers covering the crossbands.

GEORGE M. HUNT.

GEORGE C. MCNAUGHTON.
